UNITED STATES PATENT OFFICE.

FRITZ EIKENROTH, OF HERINGEN, WERRA, GERMANY.

ACETYLENE-GAS PRODUCER.

Application filed September 24, 1923. Serial No. 664,631.

To all whom it may concern:

Be it known that I, FRITZ EIKENROTH, a citizen of Germany, residing at Heringen, Werra, in the Province of Cassel, Germany, have invented certain new and useful Improvements in Acetylene-Gas Producers, of which the following is a specification.

This invention relates to acetylene gas producers, and the main object is to provide 10 a device which automatically begins producing gas when the pressure in the gasometer has been reduced to a predetermined point.

Another object is to provide a generator 15 having a raised calcium carbide hopper which is normally closed and is opened when the pressure of the gas generated by the preceding portion of calcium falls to a predetermined level.

These and other objects will become apparent in the description below, in which characters of reference refer to like-named parts in the drawing.

Referring briefly to the drawing, Figure 1 is a sectional elevational view of the gas 25 generator, showing the bell in lifted position.

Figure 2 is a sectional top plan view taken on line 2—2 of Figure 1.

Figure 3 is a sectional elevational view 30 of the carbide hopper, showing the releasing gate in closed position.

Referring in detail to the drawing, the 35 numeral 10 indicates the walls of a rectangular tub having a sloping bottom 11 at the lower end of which a tube 12 is embedded in the wall 10 and has a strap 13 secured thereto within the confines of the tub. An annular plate 14 normally covers the inner open end of the tube and has an ear projecting therefrom pivotally secured to an angular lever 15 intermediate its length, the upper end of said lever being pivotally connected to the strap, and the lower end being similarly connected to a vertically slidable 40 rod 16 which has a loop handle 17 at its upper end. The upper interior edges of the tub walls are recessed to support a platform 18 which covers the tub. The latter is at all 45 times filled with water to the level indicated in Figure 1.

At one end of the tub an inverted tank 19 is mounted in an opening formed in the platform 18 and is fixed in place by a flanged ring 20. The greater portion of the 50 length of the tank which extends into the tank is immersed in the water, and the lower

open end has a door 21, the latter being secured to a vertical shaft 22 journalled in suitable brackets, said shaft having a handle 23 at its upper end by which the door 21 is manipulated. Near the lower end of the tank an annular plate 24 is pivoted and has receptacles thereon adapted to receive the spent calcium carbide ashes.

A hopper 25 in which the calcium carbide 65 is stored, is mounted above the tank and has a casing 26 therebeneath in which a funnel 27 is mounted, said funnel directly communicating with the hopper chamber above it. The mouth of the funnel 27 may be 70 opened or closed by a gate 28 slidable on angle irons 29, the latter being in slightly inclined position. An ear 30 is rigidly secured to the underside of said gate and has one end of a connecting lever 31 secured 75 thereto. Levers 32 and 32^a are fixed on a rotatable spindle 33 which passes thru the casing. One end of the lever 32 is secured to the connecting levers 31, both the levers 31 and 32 being in the casing, the lever 32^a 80 being on the exterior side of the casing. The levers 32 and 32^a function in the manner of a bell crank. The lower end of the casing 26 is flanged and has a tube 34 secured thereto, said tube having a plurality 85 of stay rods 35 at its lower end to which a conical baffle 36 is secured. The upper end of the hopper 25 has a flanged opening normally closed by a flat plate, which seals the hopper thru the medium of a screw 37 which 90 threadably engages a yoke 38.

A gasometer tank 39 has its lower end rigidly attached to the cover 18 and is provided with a concave bottom 40 at a position near its lower end. A flanged ring 41 is 95 fixed to the upper end of the gasometer and has rods 42 rising vertically therefrom, the latter having their upper ends connected by a rod 43. A vertical bar 44 having an inverted cup 45 fixed near its upper end, is 100 secured to rod 43 intermediate its length. Said rod extends downwardly into the gasometer tank, its lower end being securely fixed to the bottom 40. A bracket 46 is attached to the upper wall of the gasometer tank 39 and has a normally vertical lever 47 pivoted thereto, the lower end of said lever being substantially circular in outline and being provided with a notch 48. An arm 49 projects from the circular end of the lever 110 and is pivotally connected to the lever 32^a on the exterior of the casing, by a bar 50.

A bell 51 having plates 52 and 52^a projecting from the top 53, is slidably mounted in the gasometer tank 39, the plates having holes therein which receive the guide rods 42. The plate 52^a has an extension 54 which engages the notch 48 at one position.

A pair of tubes 55 and 56 rise vertically in the gasometer, the upper ends opening into the bell slightly above the upper edge 10 of the gasometer, the lower ends passing thru the bottom 40 and being then bent angularly outward to pass thru the gasometer wall. The lower end of the tube 56 is coupled to and opens into a relatively small 15 container 57. The latter is directly connected to the tank 19 by piping 58. The lower end of the tube 55 also has a length of piping and is provided with a valve 59 and a filter 60, the latter having a tube 61 20 extending from its side to which outlet pipes may be attached. The top 53 of the bell is deformed into a cup 62, and a sleeve 63 which envelopes the bar 44 is rigidly mounted in said cup, the upper end projecting 25 into the same, said cup when in use being filled with water.

The operation of this gas generator is as follows. The tub 10 and the gasometer are filled with water to the levels indicated in 30 Figure 1. In Figure 1, the level of the water in the bell 51 is shown lower than the water in the gasometer 39, which is caused by the pressure of the gas in the upper chamber of the bell 51. As the gas passes out of 35 the bell thru the tube 55 and thence thru the container 60 where it is filtered by absorbent cotton and lime, to the supply outlet 61, the bell 51 will be lowered. As the bell gradually sinks to its lowest position, 40 the extension 54 of the plate 52^a rides into the notch 48 of the lever 47 and rotates said lever to the position indicated by the broken lines in Figure 1. The lever 47 in rotating lifts the bar 50 which in turn rotates the 45 levers 32 and 32^a about the spindle 33. This movement causes the gate 28 to be urged sidewise thru the medium of the lever 31 and uncovers the funnel 27. When the latter is opened, calcium carbide salts are precipitated from the hopper 25 into the tube 50 55 and fall into the tank 19. The union of the water and calcium carbide, (as is well-known) causes the release of acetylene gas which passes upwardly into the upper portion of the tank 19 and is prevented from entering the tube 34 by the conical baffle 36. The gas then passes thru the piping 58 and tube 56 into the chamber at the upper end 60 of the bell 51. As the gas is released into the bell chamber, the bell rises, and in so doing, the extension 54 rises and by contacting with the adjacent surface of lever 47, rotates the latter to vertical position, by which movement the gate 28 is shifted over 65 the open end of the funnel 27, thereby clos-

ing the latter. The inverted cup 45 mounted concentrically on the bar 44 near its upper end is rigid and does not change its position when the bell 51 is elevated. As the gas in the upper end of the bell chamber 70 causes the liquid therein to be released, said liquid will pass up thru the member 63 into member 62. As the gas generated in the device lifts the bell 51, the cup 45 will register in the flooded portion of member 62 75 and seal the opening at the upper end of the sleeve 63, thus stopping the liberation of gas or water thru this opening. The bell continues to rise as the quantity of gas increases, and, when the valve 59 is closed, an excess quantity of gas may form in the bell. This excess gas may be liberated into the atmosphere thru the sleeve 63 in the following manner. The pressure of the gas will 80 urge the water upward thru the sleeve 63 and will overflow over the top of the bell into the gasometer, thus giving the gas in the bell greater volumetric dimension. As the pressure increase continues, additional water will flow from the bell thru the sleeve 63 and will be spilled over the wall of the gasometer. In this manner the water in the bell will be decreased until the lower end of the sleeve 63 is uncovered, when the excess gas will pass thru said tube and be 85 liberated into the gasometer and the extension 54 will again rotate the lever 47, which will open the gate 28 to precipitate a new quantity of calcium carbide from which additional gas will be generated. Thus it is 90 apparent that, with this device additional calcium carbide is precipitated automatically when the gas supply has been lowered to a predetermined level.

I claim:—

1. A device of the class described comprising a tub adapted to be filled with water and having a platform covering the same, an inverted tank passing thru one end of said platform, a delivery tube in said tank, a conical baffle at the lower end of said tube, a casing on said tube, a hopper mounted on said casing having a funnel at its lower end projecting into the casing, angle irons in said casing, a gate slidable on said angle irons, a spindle in said casing, a bell crank on said spindle, a lever connecting the gate to one arm of said bell crank, said spindle when rotated being adapted to slide said gate for opening or closing the hopper funnel, a gasometer adjacent said tank, a bell slidably in said gasometer, and means on said gasometer for rotating said spindle.

2. A device of the class described comprising a tub adapted to be filled with water and having a platform covering the same, an inverted tank passing thru one end of said platform, a delivery tube in said tank, a conical baffle at the lower end of said tube, a casing on said tube, a hopper mounted on 125

said casing having a funnel at its lower end projecting into the casing, angle irons in said casing, a gate slidable on said angle irons, a spindle in said casing, a bell crank 5 on said spindle, a lever connecting the gate to one arm of said bell crank, said spindle when rotated being adapted to slide said gate for opening or closing the hopper funnel, a gasometer adjacent said tank, a bell 10 slidable in said gasometer, a bracket on said gasometer, a lever pivoted on said bracket having a notch at its lower end, an arm extending from the end of said pivoted lever, a bar connecting said arm to an arm of said 15 bell crank, said notched lever when rotated in a counter clock-wise direction being adapted to slide said gate to open the hopper funnel, and means for rotating said notched lever.

20 3. A device of the class described comprising a tub, a platform covering said tub, a

tank mounted on and passing through said platform, a casing above said tank, a hopper mounted on said casing and having a funnel at its lower end, a gate slidable in 25 said casing beneath said funnel normally closing the latter, a spindle having a bell crank thereon, a lever connecting the bell crank to said gate, a gasometer mounted adjacent said tank, a bell slidable in said 30 gasometer, plate extensions on said bell, a notched lever pivoted on said gasometer and having an arm thereon, a bar connecting said arm to said bell crank, said lever being normally in vertical position, one of said 35 plate extensions on the bell being adapted to engage the notch of said vertical lever to rotate the same to an angular position, and means for liberating excess gas from the bell.

In testimony whereof I affix my signature.
FRITZ EIKENROTH.
